INVENTOR.
Clarence A. Kissel.

BY
Thomas Donnelly
ATTORNEY.

UNITED STATES PATENT OFFICE.

CLARENCE A. KISSEL, OF LINCOLN PARK, MICHIGAN.

COMBINATION ASH TRAY AND PIPE SCRAPER.

Application filed May 21, 1927. Serial No. 193,088.

My invention relates to a new and useful improvement in a combination ash tray and pipe scraper, and has for its object the provision of a device of this class which will be 5 simple in structure, economical of manufacture and highly efficient in use.

Another object of the invention is the provision of a pipe scraper whereby, upon positioning of a pipe thereon, and pressing 10 the same downwardly, a rotating of the scraper may be effected to thoroughly and quickly scrape the interior of the pipe bowl, permitting the scrapings to fall into the ash tray.

15 Another object of the invention is the provision of a pipe scraper of this class having a threadable stem bifurcated at its upper end and carrying thereon a substantially U-shaped scraping member formed to engage 20 the sides and the bottom of a pipe bowl placed thereon.

Other objects will appear hereinafter.

The invention consists in the combination and arrangement of parts hereinafter described and claimed.

The invention will be best understood by a reference to the accompanying drawings which form a part of this specification and in which,

30 Fig. 1 is a side elevational view of the invention.

Fig. 2 is a central, vertical sectional view of the invention.

Fig. 3 is a sectional view taken on substantially line 3—3 of Fig. 2.

Fig. 4 is a fragmentary sectional view taken on substantially line 4—4 of Fig. 2.

As shown in the drawings, I have provided a saucer-like ash tray 7 having the 40 cigar rest 8 formed on its upper edge and provided with a match box holder 9. Secured to and projecting upwardly from the central portion of the base 10 of the tray is a sleeve 11 in which is positioned a coil 45 spring 12, one end of which is adapted to engage the base 10, and the other end of which is adapted to engage the lower end of a threaded stem 13. Threaded into the sleeve 11 and engaging in the threads of the stem 13 is a set screw 14. The upper end of the stem 13 is bifurcated as clearly seen in Fig. 4, and secured by rivets, or other suitable fastening means between the bifurcations is a scraping element comprising a 55 blade portion 15 and side members 16 and

17, the scraping element thus being formed substantially U-shaped.

In operation when the pipe bowl 18 is placed upon the scraper, as shown in Fig. 1 and Fig. 2, and downward pressure exerted upon the pipe bowl, the pipe bowl will be forced to the position shown in dotted lines in Fig. 2. As the stem 13 is moved downwardly the engagement of the set screw 14 in the threads of the stem 13 will effect a 60 rotation of the scraper, this thoroughly and quickly cleaning the inner surface of the pipe bowl of all foreign material, these scrapings falling to the ash tray 10.

65 It is thus evident that in addition to performing the functions of an ash tray, the combination set out will serve to effect a thorough and quick cleaning of a pipe bowl, so that the smoker may enjoy at all times a clean, fresh and sweet smoke.

70 While I have illustrated and described the preferred form of my invention I do not wish to limit myself to the precise details of structure shown, but desire to avail myself of such variations and modifications as come 75 within the scope of the appended claims.

Having thus described my invention what I claim as new and desire to secure by Letters Patent is:

1. A device of the class described comprising: a receptacle; a sleeve projecting upwardly from said receptacle; a spring mounted in said sleeve; a threaded stem in said sleeve; a screw threaded through said sleeve adjacent the upper end thereof, and 80 engaging in the threads in said stem; and a scraper carried on the upper end of said stem.

85 2. A device of the class described comprising: a receptacle; a sleeve projecting upwardly from the base of said receptacle; a spring mounted in said sleeve; a threaded stem engaging in said sleeve and engaging at its inner end one end of said spring; means projecting radially through said sleeve and engaging in the threads of said stem for effecting a rotation of said stem upon longitudinal movement of said stem relatively to said sleeve, said spring normally retaining said stem in elevated position relatively to 90 said sleeve; a substantially U-shaped scraper carried on the outer end of said stem for engaging in a pipe bowl placed thereon.

100 3. A device of the class described comprising: a receptacle; a sleeve projecting up-

wardly from the base of said receptacle adjacent the center thereof; a coil spring adjacent the center thereof; a coil spring mounted in said sleeve engaging at one end said base; a threaded stem projected into said sleeve and engaging at its inner end the other end of said spring; means projecting inwardly from the inner surface of said sleeve for engaging in the threads in said stem, the outer end of said stem being bifurcated; and a substantially U-shaped 20 scraping member mounted on said stem between its bifurcations, the bight of said U-shaped 25 scraper being formed arcuate.

4. A device of the class described comprising: a receptacle; a sleeve projecting upwardly from the base of said receptacle 15

adjacent the center thereof; a coil spring mounted in said sleeve engaging at one end said base; a threaded stem projected into said sleeve and engaging at its inner end the other end of said spring; means projecting inwardly from the inner surface of said sleeve for engaging in the threads in said stem, the outer end of said stem being bifurcated; and a substantially U-shaped 20 scraping member mounted on said stem between its bifurcations, the bight of said U-shaped 25 scraper being formed arcuate.

In testimony whereof I have signed the foregoing specification.

CLARENCE A. KISSEL.
